UNITED STATES PATENT OFFICE.

BENJAMIN F. MIESSNER, OF SOUTH ORANGE, NEW JERSEY.

SOUND-AMPLIFYING DEVICE.

Application filed June 4, 1923. Serial No. 643,152.

This invention relates to sound amplifying devices. More specifically it relates to devices adapted to receive sound waves from a sound reproducing machine and to amplify 5 such sound waves.

The invention has for some of its objects: to provide a sound amplifying device which is compact, efficient in amplifying, faithful in tone transmission, which may be manufactured at a comparatively low cost, and which is nevertheless ornamental. Other objects and 10 advantages will appear as the invention is hereinafter disclosed.

Referring to the drawings which illustrate 15 what I now consider a preferred form of the invention:

Fig. 1 is a front elevation of a sound amplifying device.

Fig. 2 is a plan view of the device shown 20 in Fig. 1.

Fig. 3 is a section taken substantially on the line 3—3 of Fig. 4.

Fig. 4 is a section taken substantially on the line 4—4 of Fig. 1.

The sound amplifying device illustrated 25 comprises generally a body portion 10 and a base or pedestal 11 for supporting the same and to which the body portion is suitably secured. The body portion 10 is shown constructed in two outwardly bulged or convexed sections 12, 13, which join substantially on a plane perpendicular to the axis of the body portion and through the line 3—3 of Fig. 4. The section or front wall 12 is shown provided adjacent its periphery with an annular series of radial slots 14 which, as will hereinafter appear, constitute outlet means or openings through which the sound waves leave the body portion of the 35 device. The sound waves to be amplified are introduced into the body portion 10 substantially centrally thereof. While other forms of means, such as a suitable tube or conduit leading from the sound box of a 40 phonograph or similar sound-reproducing machine, may be employed for supplying the sound waves to be amplified, to the body portion 10, I have selected for the purpose of illustration a means especially adapting 45 the invention for use in connection with the amplification of sound waves emanating from a translating device which receives electrical undulations and converts them into sound vibrations. This means, designated 50 15 (Fig. 4) consists of a device comprising one or more polarized electromag-

nets adapted to attract an armature suitably connected to one or more diaphragms (or a diaphragm which in itself constitutes an armature and if desired is connected to 60 one or more additional diaphragms) whereby when electrical undulations are passed through the winding of the electromagnet or electromagnets, the diaphragm or diaphragms are caused to vibrate and set up 65 sound vibrations in the surrounding medium in accordance with the electric undulations. Such translating devices are now commonly known in the art of radio telephony and need not be herein disclosed in detail. The 70 current may be supplied to the device 15 through any suitable conductors (not shown).

The translating device 15 is shown mounted in a suitable recess 16 provided in the 75 rear face of the front wall 12. A comparatively short section of divergent or frustroconical tube 17 is shown connected to the device 15 to convey the sound waves therefrom. This tube is shown surrounded by an 80 annular member 18 in order to provide a sound-conveying passage of proper and preferred form as will hereinafter appear. The inner face of the rear wall 13 is provided with an annular or cup shaped partition 19 85 having a substantially conical but curved surfaced boss 20 at its closed end to deflect the sound waves emanating from the tube 17 and impinging upon the closed end of the cup of the member 19, substantially equally 90 in all radial directions.

It will be noted that the partition 19 extends from the rear wall 13 toward the front wall 12 but terminates short of the latter. The partition 19 is surrounded by an annular or cup-shaped partition 21 which is carried by the front wall 12 and extends toward the rear wall, terminating short of the latter. The partition 17—18, the partitions 19, 21, together with the front and rear walls 12, 13, of the body portion 10, define a plurality of serially connected, sound-conveying passages or paths 25, 26, 27 and 28. The path or passage 28 surrounds the path 27, the path 27 surrounds the path 105 26 and so on. The sound waves emanating from the translating device 15 pass through the tube 17 or path 25, thence into and through the path 26 in substantially the opposite direction with respect to the direction of passage through the path 25, 110 thence into and through the path 27 in sub-

stantially the same direction as the direction of passage through the tube 17, thence into and through the passage 28 in the opposite direction and thence out through the openings 14.

Referring to Fig. 1 it will be seen that the cross-sectional area of the passage or path 27 is represented by the following formula:

$$10 \quad 3.1416(R^2 - r^2)$$

which may be written:

$$3.1416(R+r)(R-r).$$

- 15 If each of the annular passages or paths 26, 27 and 28 were so constructed as to be of constant cross-section throughout its length, i. e. $(R-r)$ a constant, and if the difference between the radii $(R-r)$ of any of these 20 three paths were the same as that of either of the other two, nevertheless the cross section of the path 28 would be greater than that of the path 27, and the cross section of the path 27 would be greater than that of the path 26. The reason for this is apparent 25 when it is borne in mind that the factor $(R+r)$ of the above formula is greater for the path 28 than for the path 27, and greater for the path 27 than for the path 26. 30 Therefore, under the assumption above made, the sound waves would travel through progressively increasing cross-sections. I prefer, in addition, to design the parts so that the longitudinal section of each path or passage 35 25, 26, 27 and 28 increases in the direction in which the sound waves travel through that path, substantially as shown in Fig. 4. In short, as the sound travels from the translating device 15 to the openings 14, 40 it passes through a conduit of continually increasing cross-section. In a sense, the effect is that of a horn having a length substantially equal to that of the dotted line (shown in Fig. 4) if the latter were straightened out.

While other shapes and materials may be adopted in the construction of the body portion 10, I have found that satisfactory results may be obtained by constructing the sections 50 12, 13 of wood by turning them about the axis A—A (Fig. 4). The member 18 may also be made of wood and turned on a lathe or other suitable wood-working machine. The slots 14 are then cut through the front wall 12. The translating device 15 is then mounted in the recess 16 and suitably secured 55 therein. The tube 17 is then inserted into the bore of the member 18 and the tube secured to the device 15. The sections 12, 13 are then secured together at their facing marginal edges, thus completing the body portion 60 10. To facilitate assembly, alignment and the connection of the sections 12, 13, the section 12 may be provided with an annular recess 30 to receive a mating annular bead

31 provided on the section 13. The body portion may be secured to the base or pedestal 11, which may also be constructed of wood, by any suitable means.

Assuming that the sound amplifying device is to be employed in connection with a radio telephony receiving apparatus the conductors or leads (not shown) of the device 15 are electrically connected to the terminals to which "loud speakers" now commonly in use are connected. If desired, the device 15 may be suitably connected to a microphone device having a stylus adapted to engage and be vibrated by the undulations in the record groove of a disc or other record of a phonograph or other sound reproducing machine. Or, as stated above, sound waves may be introduced into the body portion by a conduit leading from the sound box of a phonograph or similar sound-reproducing machine.

Instead of constructing the body portion 10 and pedestal 11 of wood, either or both may be constructed of other suitable material. For example, either or both of the body portion 10 and base 11 may be molded or pressed or otherwise formed of papier-mâché, wood pulp, or other suitable liquid or plastic material.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted and some of the features of each modification may be embodied in the others, without interfering with the more general results outlined, and the invention extends to such use.

What I claim is:

1. A sound amplifying device comprising in combination, a hollow casing, means projecting from the rear portion of said casing toward the front thereof and defining a sound-conveying passage which increases in cross-section from rear to front, means surrounding said first named means and defining a sound-conveying passage which increases in cross-section from front to rear and which is serially connected with said first named sound-conveying passage, the outer wall of said second mentioned means defining the inner wall of a sound-conveying passage serially connected with said second mentioned passage and increasing in cross-section from rear to front, means secured to and supported by the front outer end of said casing for supporting said sec-

- ond mentioned means and permitting the exit of sound waves from the front end of said third named passage, and means for supplying sound waves to the smaller end of said first named passage.
2. A sound amplifying device comprising in combination, a substantially double convex casing provided with an annular series of sound-discharging openings adjacent the periphery of its front wall, a pair of radially and endwise spaced annular partitions one of which is secured to and carried by the rear wall and extends toward the front wall and the other of which is secured to and carried by the front wall and extends toward the rear wall and surrounds the partition secured to the rear wall, the two partitions and the casing cooperating to define a tortuous sound-conveying passage which has sections which increase in cross-sectional area in the direction in which sound travels toward the sound discharging openings, means for supplying sound waves up to the inlet end of that portion of the sound-conveying passage which is defined by the inner wall of the partition which is secured to the rear wall, and a supporting base secured to the periphery of the casing.
3. A sound amplifying device comprising in combination, a casing including a front wall whose outer surface is convex at its central portion and provided with an annular series of sound-discharging openings adjacent its periphery, and a rear wall having a convex outer surface which bulges away from the front wall, the front wall being provided with a rim portion which is connected to the rim portion of the rear wall, a pair of radially and endwise spaced annular partitions one of which is secured to the rear wall and extends toward the front wall and the other of which is secured to the front wall and extends toward the rear wall and surrounds the partition secured to the rear wall, the two partitions and the casing cooperating to define a tortuous sound-conveying passage which has sections which increase in cross-sectional area in the direction in which sound travels toward the sound discharging openings, means including a translating device supported by one of the walls of the casing for supplying sound waves to the inlet end of that portion of the sound-conveying passage which is defined by the inner wall of the partition which is secured to the rear wall.
4. A sound amplifying device comprising in combination, a casing including a front wall whose outer surface is convex at its central portion and provided with an annular series of sound-discharging openings adjacent its periphery, and a rear wall having a convex outer surface which bulges away from the front wall, the front wall being provided with a rim portion which is connected to the rim portion of the rear wall, a pair of radially and endwise spaced annular partitions one of which is secured to the rear wall and extends toward the front wall and the other of which is secured to and carried by the front wall and extends toward the rear wall and surrounds the partition secured to the rear wall, the two partitions and the casing cooperating to define a tortuous sound-conveying passage which has sections which increase in cross-sectional area in the direction in which sound travels toward the sound discharging openings, means for supplying sound waves to the inlet end of that portion of the sound-conveying passage which is defined by the inner wall of the partition which is secured to the rear wall, and a supporting base secured to the periphery of the casing.
5. A sound amplifying device comprising in combination, a casing including a front wall whose outer surface is convex at its central portion and provided with an annular series of sound-discharging openings adjacent its periphery, and a rear wall having a convex outer surface which bulges away from the front wall, the front wall being provided with a rim portion which is connected to the rim portion of the rear wall, a pair of radially and endwise spaced annular partitions one of which is secured to the rear wall and extends toward the front wall and the other of which is secured to the front wall and extends toward the rear wall and surrounds the partition secured to the rear wall, the two partitions and the casing cooperating to define a tortuous sound-conveying passage which has sections which increase in cross-sectional area in the direction in which sound travels toward the sound discharging openings, means including a translating device supported by one of the walls for supplying sound waves to the inlet end of that portion of the sound-conveying passage which is defined by the inner wall of the partition which is secured to the rear wall, and a supporting base secured to the periphery of the casing.
6. A sound amplifying device comprising in combination, a casing including a front wall whose outer surface is convex at its central portion and provided with an annular series of sound-discharging openings adjacent its periphery, and a rear wall having a convex outer surface which bulges away from the front wall, the front wall being provided with a rim portion which is connected to the rim portion of the rear wall, a pair of radially and endwise spaced annular partitions one of which is secured to the rear wall and extends toward the front wall and the other of which is secured to and carried by the front wall and extends toward the rear wall and surrounds the partition secured to the rear wall, the two partitions and the casing cooperating to define a tortuous sound-conveying passage which has sections which increase in cross-sectional area in the direction in which sound travels toward the sound discharging openings, means including a translating device supported by one of the walls for supplying sound waves to the inlet end of that portion of the sound-conveying passage which is defined by the inner wall of the partition which is secured to the rear wall, and a supporting base secured to the periphery of the casing.

sections which increase in cross-sectional area in the direction in which sound travels toward the sound discharging openings, means including a translating device supported by one of said walls for supplying sound waves to the inlet end of that portion of the sound-conveying passage which is defined by the inner wall of the partition which is secured to the rear wall, and a supporting base secured to the periphery of the casing.

7. A sound amplifying device adapted to be employed in connection with a radio telephony receiving apparatus and comprising in combination; a casing including a front wall whose outer surface is convex at its central portion and provided with an annular series of sound-discharging openings adjacent its periphery, and a rear wall having a convex outer surface which bulges away from the front wall, the front wall being provided with a rim portion which overlaps and is secured to the rim portion of the rear wall, the front and rear walls consisting of molded fibrous material; a pair of radially and endwise spaced annular partitions one of which is secured to and carried by the rear wall and extends toward the front wall and the other of which is secured to and carried by the front wall and extends toward the rear wall and surrounds the partition secured to the rear wall, the two partitions and the casing cooperating to define a tortuous sound-conveying passage which has sections which increase in cross-sectional area in the direction in which sound travels toward the sound discharging openings, means including a translating device supported by one of said walls for supplying sound waves to the inlet end of that portion of the sound-conveying passage which is defined by the inner wall of the partition which is secured to the rear wall, and a supporting base secured to the periphery of the casing.

45 8. A sound amplifying device adapted to be employed in connection with a radio telephony receiving apparatus and comprising in combination; a casing including a front wall whose outer surface is convex at its central portion and provided with an annular series of sound-discharging openings adjacent its periphery, and a rear wall having a convex outer surface which bulges away from the front wall, the front wall being provided with a rim portion which overlaps and is secured to the rim portion of the rear wall; a pair of radially and endwise spaced annular partitions one of which is secured to and carried by the rear wall and extends toward the front wall and the other of which is secured to and carried by the front wall and extends toward the rear wall and surrounds the partition secured to the rear wall, the two partitions and the casing cooperating to define a tortuous sound-conveying

passage which has sections which increase in cross-sectional area in the direction in which sound travels toward the sound discharging openings, and means including a translating device supported by the front wall of the casing for supplying sound waves to the inlet end of that portion of the sound-conveying passage which is defined by the inner wall of the partition which is secured to the rear wall.

9. A sound amplifying device adapted to be employed in connection with a radio telephony receiving apparatus and comprising in combination; a casing including a front wall whose outer surface is convex at its central portion and provided with an annular series of sound-discharging openings adjacent its periphery, and a rear wall having a convex outer surface which bulges away from the front wall, the front wall being provided with a rim portion which overlaps and is secured to the rim portion of the rear wall, the front and rear walls consisting of molded fibrous material; a pair of radially and endwise spaced annular partitions one of which is secured to and carried by the rear wall and extends toward the front wall and the other of which is secured to and carried by the front wall and extends toward the rear wall and surrounds the partition secured to the rear wall, the two partitions and the casing cooperating to define a tortuous sound-conveying passage which has sections which increase in radial width in the direction in which sound travels toward the sound discharging openings, means including a translating device supported by one of said walls for supplying sound waves to the inlet end of that portion of the sound-conveying passage which is defined by the inner wall of the partition which is secured to the rear wall, and a supporting base secured to the periphery of the casing.

10. A sound amplifying device adapted to be employed in connection with a radio telephony receiving apparatus and comprising in combination; a circular casing whose axial dimension is substantially less than its diameter and including a front wall whose outer surface is convex at its central portion and provided with an annular series of sound-discharging openings adjacent its periphery, and a rear wall having a convex outer surface which bulges away from the front wall, the front wall being provided with a rim portion which overlaps and is secured to the rim portion of the rear wall, a plurality of partitions including a pair of radially and endwise spaced partitions one of which is secured to and carried by the rear wall and extends toward the front wall and the other of which pair is secured to and carried by the front wall and extends toward the rear wall and surrounds the partition secured to the rear wall.

the rear wall, the partitions and the casing cooperating to define a tortuous sound-conveying passage which has sections which increase in cross-sectional area in the direction in which sound travels toward the sound-discharging openings, means including a translating device supported by one of said walls for supplying sound waves to the inlet end of that portion of the sound-conveying passage which is defined by the inner wall of the partition which is secured to the rear wall, and a supporting base secured to the periphery of the casing.

11. A sound amplifier comprising in combination; a circular casing whose axial dimension is substantially less than its diameter; means within said casing providing a

forwardly flaring axial passage; means including a rearwardly-extending partition member forming a passage surrounding the axial passage and communicating with the forward end thereof and extending rearwardly and outwardly therefrom, and a sound delivery passage surrounding the second said passage and communicating with the rear end thereof and extending forward therefrom; and means secured to the forward end of said casing and extending across said sound-delivery passage at its forward outlet end for supporting said rearwardly-extending partition member from said casing.

In testimony whereof I hereto affix my signature.

BENJAMIN F. MIESSNER.
